UNITED STATES PATENT OFFICE.

FRANK L. BERRY, OF SPOKANE, WASHINGTON.

PNEUMATIC AGITATOR FOR ICE-MAKING APPARATUS.

1,113,298.

Specification of Letters Patent.

Patented Oct. 13, 1914.

Application filed September 28, 1910, Serial No. 584,168. Renewed November 12, 1913. Serial No. 800,862.

To all whom it may concern:

Be it known that I, FRANK L. BERRY, a citizen of the United States, residing at Spokane, in the county of Spokane and State of Washington, have invented certain new and useful Improvements in Pneumatic Agitators for Ice-Making Apparatus, of which the following is a specification.

This invention pertains to pneumatic agitators for artificially freezing ice, and has for its purpose to provide a more efficient means of keeping the water agitated during the freezing process and of removing the mechanical construction whereby the water is kept agitated, after the freezing process is complete.

Other purposes and objects will be herein-after described and shown in the accompanying drawings in which—

20 Figure 1, is a transverse vertical sectional view of my improved pneumatic agitator. Fig. 2 is a combined front elevation and longitudinal sectional view of the improved construction for agitation purposes, Fig. 3 is an elevation of the construction shown in Fig. 2 set at an angle of forty-five degrees, and Fig. 4, is an elevation of the tube used for thawing purposes, together with connections and adapted for insertion in the 30 inner tube shown in Fig. 2.

The water can H is incased by the cover a, timbers b, side walls d, and bottom f. The ammonia coils c are arranged in the usual manner within the supports d. A bottom e is arranged for the can H.

40 A combined cross-bar and casing A is adapted for setting across the top of the can H and for being held rigid in that position. Carrier pins E adapted for disappearing within cavities in the ends of the combined cross-bar and casing A are regulated by means of the coil springs D and releasing pins K operating in the angular slots L. In Fig. 2 the line Z—Z indicates the dividing line between the elevation and sectioned portions, the former being to the left and the latter to the right thereof. An air tube B extends downward at right angles with the combined cross-bar and casing A and connects with the air inlet J, has perforations h, i, j, k, l, m, n, p, r, s, down the sides thereof and an opening M at the bottom thereof. A tube C reaches from the top of the combined cross-bar and casing A, extends down-

ward within the tube B to a point near the bottom thereof and is open at the top N thereof and closed at the bottom. A cavity O is left between the outer tube B and inner one C. The thawing tube R is notched S at the bottom, has a collar Q near the top 60 and a hose connection P at the top thereof. A hose G connects with the air inlet J leading to the cavity O. The air supply pipe F connects with the hose G.

In the practical application of the invention, the can H is filled with water to the line I, air is turned into the pipe F, passes through the hose G into the cavity O and passes out through the perforations h, i, j, k, l, m, n, p, r, s and the opening M whereby 70 the water in the can is kept agitated. The freezing process begins at the bottom of the can and extends upward. The tube B is frozen into the water gradually from the lower end up. After the lower end is frozen 75 in and the opening M no longer gives vent to the air, the same passes through the perforations in the tube along the sides thereof, thereby keeping what water that is not frozen in a state of agitation until it is 80 frozen to the surface. After the freezing process is complete the tube B is thawed from the ice by heat passed through the tube R after the same has been inserted into the inner tube C at the opening N, the heat passing 85 out at the notch S at the bottom thereof. By forcing back the carrier pins E the tubes may then be removed from the ice block. The tube C provides an open passage for the insertion of the thawing tube R. 90

The carrier pins E are held into the cavities in the combined cross-bar and casing A by the pins K attached thereto and thrown into the lower ends of the slots L while the apparatus is attached to the can 95 as shown in Fig. 1, and thrown out as shown in Fig. 2 by the reverse process, so as to afford a means for removing the parts.

Having thus described my invention, what I claim as new and useful and desire to secure by Letters-Patent, is:

In a pneumatic agitator for ice making apparatus, the combination with a can-refrigerating receptacle, of a combined cross-bar and casing three vertical tubes one with- 105 in the other extending downwardly from the cross bar into the can-refrigerating receptacle, the outside tube being perforated

on sides and bottom and open at the top and
adapted for connection with an air supply
pipe, the intermediate tube having an open
top and closed sides and bottom and the
5 inner tube having closed sides and openings
at the bottom and open at the top and adapt-
ed for connection with a heat supply pipe.

In testimony whereof I affix my signature,
in presence of two witnesses.

FRANK L. BERRY.
